CEMENTITIOUS STRUCTURAL UNIT

William E. S. Strong, New York, N. Y., assignor
to John B. Pierce Foundation, New York, N. Y.,
a corporation of New York

Application October 31, 1939, Serial No. 302,085

3 Claims. (Cl. 72—36)

This invention relates to structural units and to assemblies thereof in building construction.

The invention constitutes an improvement over the structural unit disclosed and claimed in my United States Patent No. 2,096,265, granted October 19, 1937.

Both the patented invention aforementioned and the one here disclosed are directed particularly to a structural unit of substantially slab formation especially adapted for convenient and secure joinder to like units in the erection of structure, such as the walls, roof, or floor of a building. The structural unit advantageously embodies a mass of insulating material within the body thereof.

In the patented construction aforementioned, the structural unit is disclosed, in a specific form, as composite. One portion is formed as a rectangular concrete shell for receiving insulating material, and the other portion as a cover for confining the insulating material within the shell. The thus provided concrete structural unit is of slab formation having two broad faces separated by an appropriate thickness which provides a measure of the insulating value of the unit.

Around the outer margins of the peripheral walls which define the recess in the shell for receiving insulating materials, are spaced marginal indentations of such size as will afford adequate opportunity for manipulating securing means, such as bolts and nuts, within the pocket recesses formed when the marginal indentations of respective juxtaposed units register. A reinforcing framework, incorporated in the concrete shell, traverses the lateral openings of the marginal indentations forming pockets, so that bolts and nuts or other suitable joinder means may be employed, in conjunction with the framework, to secure juxtaposed units tightly to one another.

The present construction is similar in its essentials to the above described prior construction, but constitutes an improvement thereover in that a greater facility and ease of securement of assembled structural units, as well as economies in the manufacture of the units, are afforded.

In the prior construction, marginal indentations are interposed along the lengths of the peripheral walls of the shell, between the corners of the shell. In the present construction the corners of the shell are, in effect, partially clipped off diagonally so that the reinforcing frame provides thereat pockets which correspond to the marginal indentations of the prior construction.

In this manner there is provided a structural unit which can be readily united at each of its corners with corners of other structural units, or with suitable other structure, the securement of each group of contiguous corners being achieved within the confines of a single passage defined by the "clipped" corners of the shell portions of the structural units.

By this simplified manner of securement, greater tightness of joint is had, and stresses are more evenly distributed.

In the drawing:

Fig. 1 represents an elevation of that broad face of one embodiment of structural unit pursuant to the invention which is adapted to provide the inside face of a wall or similar structure built up from a plurality of the structural units;

Fig. 2 represents an enlarged vertical section taken on the line 2—2, Fig. 1, illustrating only the concrete shell and reinforcing framework;

Fig. 3 is a view similar to that of Fig. 2 but illustrating the complete structural unit;

Fig. 4 represents an enlarged fragmentary view of mutually secured four contiguous corners of respective structural units, similar to those of Fig. 1, as assembled in a wall or other structural portion of building construction; and

Fig. 5 represents an enlarged fragmentary vertical section taken on the line 5—5, Fig. 4.

As is the case in the prior patent, the structural unit is specifically illustrated as rectangular in configuration. While it is practical and convenient to employ rectangular building units for construction purposes, it is realized that other polygonal configurations may also be employed without sacrificing essential structural features of the invention.

The composite structural unit illustrated in Fig. 1 comprises a recessed body shell 10 molded into final form from a plastic cementitious mixture; an angle-iron reinforcing framework 11; vermiculite insulating material 12; and a cover plate 13 molded from plastic cementitious material.

It is contemplated that concrete or other cementitious mixture will be the material usually employed in the forming of the recessed shell and cover plate of the unit, and that structural steel shapes, especially angle-irons, will be employed for the reinforcing framework, but it is within the scope of the invention to form the recessed shell and cover plate of any materials found suitable for the purpose, the two elements not necessarily being formed from similar mate-

rials; and it is within the scope of the invention to form the reinforcing framework of any rigid material found suitable for the purpose. The insulating material may be vermiculite, loose or compacted, or may be any other insulating material found suitable for the purpose.

The recessed body shell 10 has a portion 10a of substantially slab formation in which may be incorporated reinforcing wire mesh 14 or the like. The outer face of the slab portion 10a may be provided with any desired contour, as for instance the contour indicated 10a-1 designed to give a clapboard effect. Along the peripheral margin of the slab portion 10a, walls 10b project outwardly, preferably at right angles to the slab portion, and extend in substantially unbroken continuity. It should be noted, however, that while the slab portion 10a has fully formed corners, the peripheral walls 10b cut diagonally across the corners, as at 10b-1, giving the effect of clipped corners. The walls 10b and wall portions 10b-1 advantageously project equally from the inner face of slab portion 10a for the purpose of receiving the cover plate 13 in such manner as to seal the insulating material 12 within the recess 10-1 of the body shell 10.

Intermediate the outer face 10a-1 of slab portion 10a and the free terminal ends of projecting peripheral walls 10b and wall portions 10b-1 is disposed the reinforcing framework 11. The framework has the same length and width as the recessed body shell, and, as illustrated, is advantageously formed from angle-irons. The angle-irons are associated so that a set of similar legs 11a lie in a common plane directed inwardly of the framework, and so that the remaining set of similar legs extend in a common direction at substantially right angles from such plane.

The framework 11 is advantageously incorporated with the recessed body shell 10 during the molding thereof in such manner that the set of legs 11a, which lie in a common plane, serve to reinforce the peripheral margins of the slab portion 10a, and the other set of legs 11b serve to reinforce the lateral peripheral walls 10b of the shell.

The legs 11b of the framework thus tend to complete the corners cut short by the wall portions 10b-1, see especially Fig. 1, and provide marginal pockets 15 at the corners of the recessed body shell. As illustrated in Figs. 2 and 3, these legs 11b may be drilled, see 16, for the purpose of receiving bolts in the securing of juxtaposed units to one another, or of securing the one unit to other supporting structure.

The flake vermiculite 12, or other suitable insulating material, is inserted in the recess 10-1 of the body shell 10 in such quantity as to entirely fill the recess when the cover plate 13 is applied. The cover plate is advantageously formed of the same type of cementitious material as is the body shell 10, but is produced in the form of a flat plate of such dimension as to fit over the recess 10-1 and to rest on the free terminal ends of peripheral walls 10b and wall portions 10b-1. It may be joined to the walls upon which it rests by means of a suitable waterproof mastic, or, preferably, by mechanical securing means such as screws. The corners of the plate 13 may be clipped shorter than just the proper fit to provide grooves 17, see Fig. 3, for the reception of a small cover plate to be hereinafter described.

In certain instances, the insulating material 12 may be in solid block form and attached to

the inside surface of the cover plate; or, in itself, may provide the cover plate.

The structural units thus formed may be assembled in juxtaposed position in building construction. The corner pockets 15 and the corner portions of reinforcing framework 11 then provide a most convenient means of securely joining the units to one another. Four contiguous corners of respective units, see Fig. 4, provide a pocket recess 18 traversed by two diagonals formed by the contiguous corner portions of angle-iron legs 11b of the respective structural units. Bolts and nuts, as at 19, may be employed in conjunction with the receiving holes 16 for securely uniting the contiguous angle-iron leg portions 11b, and, thus, the contiguous structural units, together.

A small cover plate 20, similar in material and general formation to the cover plate 13, may be employed to cover the pocket recess 18. Such cover plate 20 fits into the grooves 17, disposed at the corners of the structural units, and rests upon the wall portions 10b-1, thus providing continuity of wall surface.

It will be obvious that one or more of the units may be joined singly or mutually to other structure in building construction in much the same manner disclosed in Figs. 4 and 5, if found desirable.

The marginal corner indentations formed in the recessed body shell may be configurated as found convenient in the particular instance, the illustrated configuration being merely an example of a preferred type.

The weathertight joint illustrated at 21, Fig. 5, and provided by reason of the peripheral grooves 21a formed about the lateral peripheral walls of the body shell 10, is no part of the present invention, and consequently is not described in detail. It is fully disclosed and claimed in my U. S. Patent No. 2,117,377, issued May 17, 1938, and entitled Atmospheric protected flexible joint for building units.

While this invention has been illustrated and described with respect to only one specific embodiment thereof, it is to be distinctly understood that many changes may be made without departing from the generic scope of the invention as set forth herein and in the claims that follow.

50 I claim:

1. A structural unit of slab formation having substantially straight bounding edge faces and angular corners and comprising a slab portion proper, and frame elements defining said angular corners and secured to said slab portion proper, the corners of said slab portion proper being clipped substantially diagonally to form substantially triangular corner recesses between said slab portion proper and said frame elements, said triangular corner recesses opening into a major face of said structural unit and providing means for joining said structural unit to other structure.

2. A structural unit of slab formation having substantially straight bounding edge faces and angular corners, and comprising a slab portion proper which is composite in nature including a recessed shell element, insulating material within the recess of said shell element, and a slab cover secured over the opening of said recess, and a peripheral frame secured about the said slab portion proper along said bounding edge faces of said structural unit and defining said angular corners thereof, the corners of said slab portion proper being clipped substantially diagonally to form substantially triangular corner

recesses opening into a major face of said structural unit and providing means for joining said structural unit to other structure.

3. In building construction, a plurality of structural units of slab formation arranged together so that their corners mutually intersect, each of said structural units comprising a slab portion proper and frame elements defining said angular corners and secured to said slab portion proper, the corners of said slab portion proper being clipped substantially diagonally to form substantially triangular corner recesses between

5 said slab portion proper and said frame elements, said triangular corner recesses opening into a major face of said structural unit and providing means for joining said structural unit to other structure, said structural units being so arranged that their mutually intersecting corners form pocket recesses, and means securing the frame elements of said structural units at said mutually intersecting corners thereof, and within the said 10 pocket recesses.

WILLIAM E. S. STRONG.
